UNITED STATES PATENT OFFICE.

CHARLES W. HUNTINGTON, OF NORWICH, CONNECTICUT, ASSIGNOR TO
WILLIAM A. AIKEN, OF SAME PLACE.

ADJUSTABLE JOINT FOR DISPLAY-FRAMES.

SPECIFICATION forming part of Letters Patent No. 437,650, dated September 30, 1890.

Application filed June 14, 1890. Serial No. 355,434. (No model.)

To all whom it may concern:

Be it known that I, CHARLES W. HUNTINGTON, a citizen of the United States, residing at Norwich, in the county of New London and 5 State of Connecticut, have invented a certain new and useful Improvement in Adjustable Joints for Display-Frames, which improvement is fully set forth and described in the following specification, reference being had 10 to the accompanying sheet of drawings, in which—

Figure 1 shows portions of an upright and lateral arm connected by a joint of my improved form, and Fig. 2 is a similar view from the rear or opposite side. Fig. 3 is a cross-sectional view of said joint on line xx of Fig. 1; and Figs. 4 and 5 are perspective views of certain parts of said joint, more particularly referred to hereinafter. Fig. 6 shows inner 15 face and edge views of the ratchet-disk of arm b , and Fig. 7 similar views of the movable ratchet-disk k .

My invention seeks to provide a joint that may be advantageously used in display-frames, head-rests for photographers' use, and 20 all articles of like character in which it is desired or necessary to adjust certain parts to different positions; and my object is to produce a joint of great strength, that may be 25 readily adjusted, and which is capable of being produced in pleasing design.

In the annexed drawings, the letter a indicates a rod, which may represent the rigid upright or standard of a display-frame; b , a 30 notched lateral arm of well-known form, and c a collar fitted on upright a and clamped thereto by a screw d or similar device.

It should be understood that the means employed to clamp collar d to the upright forms 35 no part of my invention.

The inner end of arm b is formed as a disk b' , that is bored centrally and provided on one face with a series of ratchet-teeth e , cut substantially like those of a face-mill.

On the collar c is a disk c' , that has a square 40 central opening c^2 , and is cupped to form a recess c^3 of considerable depth, the outer diameter of disk c' being the same as that of the disk on arm b , and the diameter of the 45 recess c^3 being such that the described toothed projection e may freely enter therein, as illus-

trated in Fig. 3 of the drawings. The two disk-sections are secured together by a stud f and screw g , the former of which is round adjacent to its head f' for a distance equal to 55 the thickness of disk b' , and throughout the rest of its length is squared and of such size that it may enter snugly in the corresponding opening c^2 in the cupped disk c' . The squared end of stud f is drilled and tapped 60 to receive the screw g , whose head is somewhat larger than the end of the stud, as plainly shown. It will now be understood that when the disks are assembled and secured together by stud f and screw g they (the disks) may be 65 partially rotated on each other, but cannot be separated until screw g is removed.

k denotes a disk having a square central hole of size to fit loosely on squared part of stud f , and having on one face a series of 70 ratchet-teeth adapted to engage and interlock with those of the described teeth on disk b' .

When the several parts of the joint are assembled, disk k is free to slide on stud f , but is held normally in locking engagement with 75 the companion ratchet-disk by a spring m , that is compressed between disk k and the bottom wall of recess c^3 . To throw the teeth of said disk k out of engagement with those of the companion disk, I have provided a push- 80 button n , having a stem n' , that fits loosely in a central hole in stud f , and is provided with trunnions n^2 , that extend outward through slots f^2 in said stud. When button n is pressed, the trunnions n^2 press back the disk k against 85 the force of spring m , when the arm b may be lowered. On discontinuing the pressure on button n the spring m immediately acts to bring the ratchet-disks again into locking engagement. When it is desired to raise arm 90 b , it is only necessary to grasp said arm and swing it upward to the desired inclination, the ratchet-teeth meanwhile riding on each other and forcing disk k inward against the expansive force of spring m .

My described joint is of simple construction. Most of the operative parts are concealed from view and protected from dust, &c., and the whole device is of pleasing design.

Having described my invention, I claim— 100

1. An adjustable joint consisting of two disks, one being cupped and the other formed

with ratchet-teeth, as set forth, a spring-pressed ratchet-disk within said cupped disk, and means, substantially as described, for moving said spring-pressed disk out of engagement with its companion disk, said elements being combined substantially as specified.

5 2. In combination with a cupped disk, a disk of corresponding diameter formed with ratchet-teeth, as set forth, a headed stud with body portion squared to enter a corresponding open-

ing in said cupped disk, a screw tapped into the squared end of said stud, as set forth, a spring-pressed toothed disk movable on said stud, and means, as set forth, for moving said spring-pressed disk out of locking engagement with its companion disk. 15

CHARLES W. HUNTINGTON.
